United States Patent Office.

CHARLES J. BEASLEY, OF PETERSBURG, VIRGINIA, ASSIGNOR TO HIMSELF AND TAPPEY, LUMSDEN & COMPANY, OF SAME PLACE.

Letters Patent No. 94,993, dated September 21, 1869.

IMPROVEMENT IN COTTON-PRESSES.

The Schedule referred to in these Letters Patent and making part of the same.

To all whom it may concern:

Be it known that I, CHARLES J. BEASLEY, of Petersburg, in the county of Dinwiddie, and State of Virginia, have invented a new and useful Improvement in Cotton-Presses; and I do hereby declare that the following is a full, clear, and exact description thereof, which will enable others skilled in the art to make and use the same, reference being had to the accompanying drawing, forming part of this specification.

This invention relates to improvements in cotton-presses, having for its object an improved arrangement of means whereby the follower may be worked both up and down by the same operating-lever, working in the same way; also, a simple arrangement for varying the leverage, as the force acquired is greater or less; also, an improved arrangement of the follower, to facilitate filling the case.

Figure 1 represents a side elevation, partly in section;

Figure 2 represents an end view; and

Figure 3 represents a plan view of the same.

Similar letters of reference indicate corresponding parts.

The follower A is journalled to the rods B at C, and works vertically in the case.

These rods pass through moving blocks D and retaining blocks E, containing eccentric pawls F, capable of working the rods either upward or downward.

They are provided with weighted handles G, by which they are turned either way, so as to engage the rods by either point. As represented in the drawing, they are adjusted for working the rods downward.

The blocks D are connected by rods H to levers I, at the junction of short right-angled arms I', which

are pivoted to suspending-arms K of the holding-blocks, which arms are pivoted to supporting-lugs, at L, projecting from the case.

The vibration of these levers will draw the follower down when the pawls are adjusted to the positions represented in the drawings, and upward when the said pawls are turned the other way.

When the levers are nearest the vertical line their throw of the blocks D will be greatest, and when nearest the horizontal line the throw will be least. In this way the throw of the levers may be varied according to the resistance.

When the follower is raised above the top of the case it may be turned on its journals edgewise, as shown at K, and the rods B, on which it is supported, may be turned away to one side of the case, to admit of filling the case through the top.

Having thus described my invention,

What I claim as new, and desire to secure by Letters Patent, is—

1. The combination, with reciprocating rods B and a follower, K, of a shaft, which turns in its bearings above the frame, to allow ingress to the cotton, in the manner described.

2. The combination of a lever, having a fixed fulcrum, with an arm, H, and movable grasper D, to pull the reciprocating rods B downward, in the manner described.

3. The combination, with the depressing-device mentioned in second clause, of a stationary guide and frictional detainer E, arranged as set forth.

CHARLES J. BEASLEY.
